TIME LAG FUSES WITH FUSE LINKS HAVING LINK-SEVERING OVERLAYS

Frederick J. Kozacka, South Hampton, N.H., assignor to
The Chase-Shawmut Company, Newburyport, Mass.

Filed Jan. 30, 1963, Ser. No. 255,732

12 Claims. (Cl. 200—123)

This application is a continuation-in-part of my co-pending patent application Ser. No. 116,365, filed June 12, 1961, for Time Lag Fuses of the Blade Contact Type, now U.S. Patent 3,123,693, issued March 3, 1964.

This invention has reference to electric fuses, and more particularly to time-lag fuses.

It is a general object of this invention to provide improved time-lag fuses, and more particularly time-lag fuses having sufficient time-lag to preclude blowing thereof on motor starting inrush currents when included in a motor circuit.

It is another object of this invention to provide improved time-lag fuses wherein the required blowing delay on occurrence of overload currents is achieved by an overlay on a fuse link of a metal having a lower fusing point than the base metal of which the fuse link is made, causing severance of the fuse link by a metallurgical reaction when the fusing point of the overlay is reached.

Relatively long time-lags may be achieved by designing the fuse links of time-lag fuses of the above description in such a fashion that the fuse links comprise relatively large amounts of metal and have such a geometry as to effectively minimize the rate of rise of temperature of the overlay metal on occurrence of relatively large overload currents, and by further providing means tending to minimize heat losses of the fuse structure as a whole to the space surrounding the fuse structure on occurrence of relatively small overload currents. The latter means are in the nature of thermal insulators, minimizing heat exchange between the fuse structure and the space surrounding the same, and thus tending to minimize the minimum current required for causing fusion of the overlay and consequent severance of the base metal at the point where the overlay is located. Heat dissipation at relatively small overload currents may be minimized by providing fuses with a composite ribbon fuse link structure comprising a first portion having about the same width as the blade contacts of the fuse and being arranged relatively close to the longitudinal axis of the casing, and further comprising a second portion arranged generally more remotely from said longitudinal axis and overlapping and shunting said first portion. The link-severing overlays of a metal having a lower fusing point than the base metal extend transversely across the above mentioned first portion and transversely across the above mentioned second portion of the ribbon fuse link structure. This geometry is, however, in itself not always sufficient to limit the heat exchange between the fuse structure as a whole and the ambient space to the extent required for obtaining a time-current characteristic of the type needed for time-lag fuses intended for application in motor circuits. To achieve this end it is further generally necessary to apply as a pulverulent arc-quenching filler a substance having a relatively small thermal conductivity. The thermal conductivity of the filler must generally be smaller than that of quartz sand in order to comply with the highest time lag requirements, which requirements are in the order of ten seconds for overloads in the order of five times the rated current. An arc-quenching filler having such a small thermal conductivity is, for instance, gypsum. Gypsum and other pulverulent arc-quenching fuse fillers having a thermal conductivity of the same order as gypsum tend to generate but rela-

2

tively small arc voltages. This, in turn, tends to limit the interrupting capacity of a given fuse structure unless the fuse link structure is designed to form a relatively large number of series breaks on occurrence of large fault currents such as short-circuit currents. The provision of fuse link structures designed to form a relatively large number of series breaks on occurrence of relatively large fault currents is conducive to excessive watt losses during the extended periods of time during which a fuse link performs its normal current-carrying duty. Therefore it is desired to limit the number of series necks or serially related points of reduced cross-section forming series breaks on occurrence of major fault currents.

It is another object of this invention to provide time-lag fuses wherein interruption is effected in the overload range by a metallurgical reaction between an overlay metal having a relatively low fusing point and a base metal having a relatively high fusing point, which fuses lend themselves to be designed for the highest time-delay requirements which may be imposed in connection with motor circuits, and in which fuses the high thermal insulating action of the pulverulent arc-quenching filler is not achieved at the price of relatively small arc voltage generating performance thereof.

The design of time-lag fuses of the type having link-severing low fusing point metal overlays and adapted for application in motor circuits is particularly difficult in the case of fuses having a relatively small voltage rating, e.g. a rating of 250 volts. This is due to the fact that fuses having a relatively small voltage rating comprise relatively compact casings, resulting in a closer proximity between fuse link and casing surface than in case of fuses having a relatively high voltage rating and relatively large casings, and that heat exchange with the ambient atmosphere tends to increase the closer the fuse link structure is arranged to the casing surface.

The following data taken from the Standards for Safety Fuses of the Underwriters' Laboratories, Inc., are indicative of the relative size of the casings, and consequently of the relative proximity between casing surface and fuse link structure, in fuses having a voltage rating of 250 volts, and 600 volts, respectively.

45	Volts	Amps.	Length over Terminals, inches	Minimum Dis- tance from Midpoint of Casing to Nearest Live Part, inches
50	250	201-400	8 $\frac{5}{8}$ $\pm$ 3 $\frac{1}{2}$	1.187
	600	201-400	11 $\frac{1}{8}$ $\pm$ 3 $\frac{1}{2}$	2.500
	250	401-600	10 $\frac{1}{8}$ $\pm$ 3 $\frac{1}{2}$	1.531
	600	401-600	13 $\frac{3}{8}$ $\pm$ 3 $\frac{1}{2}$	2.687

It is, therefore, another object of the invention to provide time-lag fuses of the type having link-severing low fusing point metal overlays and adapted for application in motor circuits which fuses are designed for voltage ratings below 600 volts, say 250 volts, and which fuses have compact casings, and in particular casings of sizes standardized in the above referred-to fuse standard of the Underwriters' Laboratories, Inc.

Still another object of the invention is to provide time-lag fuses having the above referred-to link severing means capable of achieving relatively long blowing delays and including quartz sand as arc-quenching filler.

I have found that the two conditions of using quartz sand as a highly effective arc-quenching medium and to provide a pulverulent thermally insulating filler which has a considerably smaller thermal conductivity than normally encountered with quartz sand are quite compatible rather than incompatible, as thought heretofore. These two conditions can be met by filling the casings of fuses

with a mixture of quartz sand whose constituent particles are coated with a powder having a much smaller thermal conductivity than quartz sand, imparting to the composite filler a much smaller thermal conductivity than pure quartz sand. The mixture between quartz sand, or granular quartz, and an additional pulverulent arc-quenching filler having a substantially smaller thermal conductivity than quartz sand as such should be intimate. The additional arc-quenching filler which may, for instance, be gypsum should have a substantially smaller average particle size than the quartz sand. The intimate mixture of granular quartz and the additional pulverulent arc-quenching filler should embed all serially arranged points of reduced cross-section of the ribbon fuse link and the link severing low fusing point metal overlay thereon. On occurrence of major fault currents and formation of series breaks the granular quartz particles, though coated with a gypsum, or other medium having a thermal conductivity of the same order as gypsum, fuse rapidly, thereby absorbing relatively large amounts of heat and generating relatively high arc voltages. As long as the fuse structure is intact and performs its normal current-carrying duty the thermal conductivity of the filler is relatively small because many particles of quartz sand are coated with, and thermally insulated from, the adjacent particles of quartz sand by layers of gypsum or a like relatively poor conductor of heat.

For a better understanding of the invention reference may be had to the accompanying drawings wherein

FIG. 1 is substantially a vertical section of an electric fuse embodying the present invention showing some parts thereof, including the ribbon type fuse link structure, in elevation rather than in vertical section;

FIG. 2 is a section along 2-2 of FIG. 1;

FIG. 3 is a section along 3-3 of FIG. 1;

FIG. 4 is a photomicrograph of pure screened quartz sand; and

FIG. 5 is a photomicrograph of pure screened quartz sand coated with gypsum powder, the magnification of FIG. 5 being the same as that of FIG. 4.

Referring now to the drawings, and more particularly to FIGS. 1-3 thereof, numeral 1 has been applied to indicate a casing of insulating material closed on both ends thereof by terminal plates 2. Each terminal plate 2 supports one of a pair of blade contacts 5. Each blade contact 5 is provided with a pair of prongs adapted to be inserted into a pair of registering apertures in terminal plates 4 and to thereafter be upset in rivet fashion, thus firmly securing blade contacts 5 to terminal plates 2. Reference numeral 4 has been applied to indicate the upset ends of the aforementioned prongs of blade contacts 5. Casing 1 is provided with four internal reinforcement ribs 1a which are angularly displaced 90 degrees and extend in a direction longitudinally of casing 1. Terminal plates 2 are screwed against the ends of casing 1 by screws 6 projecting axially into reinforcement ribs 1a. Preferably asbestos washers (not shown) are interposed between the ends of casing 1 and terminal plates 2. A pair of multi-perforated fuse links L₅, L_{5'}, L₆ interconnects conductively the axially inner surfaces of terminal plates 2. The aforementioned fuse links are substantially channel-shaped, each including a web portion L₅ having substantially the same width as that of blade contacts 5. Each web portion L₅ has an axial extension L₅', and the axial extensions L_{5'} of links L₅, L_{5'}, L₆ flare outwardly toward terminal plates 2 having the axially outer end affixed to terminal plates 2. Reference numeral 3 has been applied to indicate spot welds between the axially outer ends of link extensions L_{5'} and terminal plates 2. Each of the channel-shaped fuse links or fusible elements L₅, L_{5'}, L₆ conductively interconnecting terminal plates 2 includes a pair of integral flange portions L₆ each enclosing an angle of less than 90 degrees with the aforementioned web portions L₅. Web portions L₅ and flange portions L₆ are preferably made of an integral sheet of metal having a

relatively high conductivity and a relatively high fusing point such as copper or silver. Each fuse link L₅, L_{5'}, L₆ is provided with an overlay 8 of a low-fusing point link-severing metal, preferably tin, or an alloy including tin. Each overlay extends transversely across the web portion L₅ and the two flange portions L₆ of each of the fuse links L₅, L_{5'}, L₆. Each fuse link L₅, L_{5'}, L₆ is provided with several, i.e. three to five, transverse lines 9 of circular perforations, and with a larger number of longitudinal lines 12 of circular perforations. In other words, the number of perforations in each transverse line 9 by far exceeds the number of perforations in each longitudinal line 12. Overlays 8 extend parallel to the transverse center lines 9 of perforations and jut into the spaces defined by contiguous perforations of said lines, without projecting significantly beyond the center lines of narrowest cross-section of links L₅, L_{5'}, L₆ defined by their respective transverse center line 9 of perforations. Overlays 8 extend over the entire width of fuse links L₅, L_{5'}, L₆, i.e. they are coextensive with the width of the web portion L₅ and with the width of the two flange portions L₆ of each fuse link. Casing 1 is filled with a pulverulent arc-quenching filler 11 indicated only in portions of FIGS. 1-3 and broken away, or deleted, in other portions thereof. Filler 11 is an intimate mixture of granular quartz and of an additional pulverulent arc-quenching filler having a substantially smaller thermal conductivity than granular quartz as such. Filler 11 embeds all of fuse links L₅, L_{5'}, L₆, including all their zones of reduced cross-section formed by their transverse lines of perforations 9 and also their link-severing overlays 8. The aforementioned additional filler has a substantially smaller average particle size than said granular quartz. The additional filler phase of mixed filler 11 is sufficiently high to extend the fusing time of overlays 8 at currents in the order of five times the rated current of the fuse to the order of several seconds, e.g. ten seconds. To achieve this end without increasing the size of casing 1 beyond what the standards now prevailing in the United States of America prescribe the percentage of the additional small thermal conductivity filler must be relatively large, e.g. 30 percent, and the composite filler must have a thermal conductivity closer to that of the additional filler than to that of quartz sand as such.

The flange portions L₆ form thermal shields precluding heat generated in web portions L₅ from freely reaching casing 1 and being readily dissipated. Flange portions L₆ form also shunts, shunting away from web portions L₅ a substantial percentage of the electric current carried by blade contacts 5. Operating as thermal shields flange portions L₆ keep the heat generated by the fuse links close to the axis region of casing 1. The axial extensions L_{5'} of the fuse link have a smaller cross-section than the axially inner portions L₅, L₆ thereof and their ohmic resistance is consequently relatively high. As a result, axial extensions L_{5'} form heat dams tending to limit heat exchange in a direction longitudinally of the fuse structure. These heat exchange limiting features of the fuse link structure L₅, L_{5'}, L₆ and its relatively large mass and heat absorbing capacity coupled with the relatively small thermal conductivity of the arc-quenching filler 11 account for the fact that the minimum fusing currents of structures of the type shown in FIGS. 1-3 are relatively small, and the time delays thereof relatively long, e.g. as long as ten seconds at protracted overloads in the order of five times the rated current. The concept of rated current is defined differently in various fuse standards and, therefore, this term should preferably be defined specifically wherever lack of such a definition may result in ambiguity. In this context, wherever the term rated current is used, this term is understood to mean minimum fusing current divided by 1.3, the figure 1.3 being known as the fusing factor. The statement that fuses embodying this invention achieve time lags in the order of seconds, and as high as ten seconds, on occur-

rence of overloads in the order of five times the rated current may, therefore, also be expressed in terms of minimum fusing current. This statement then takes the form that fuses embodying this invention achieve time-lags in the order of seconds, and as high as ten seconds, on occurrence of overloads in the order of $5:1.3=3.8$ times the minimum fusing current.

On occurrence of relatively small overloads of inadmissible duration the link-severing overlays 8 fuse initially at the radially inner portions L_5 of the composite link structure and sever these portions by a metallurgical reaction. This greatly increases the current density and heating action of the radially outer portions L_6 of the composite link structure, causing the same to be severed by a metallurgical reaction rapidly following that causing the radially inner portions L_5 of the composite link structure to be severed.

On occurrence of major faults series breaks are formed, one at each transverse line 9 of perforations generating a sufficiently high aggregate arc voltage to bring the fault current rapidly down to zero. Because of the particular geometry of the composite fuse link structure and its resulting magnetic action, the current density in the web portions L_5 exceeds the current density in the flange portions L_6 . Consequently the initiation of the formation of each break begins in the web portion L_5 of each transverse line 9 of perforations and progresses to the flange portions L_6 thereof. Therefore arc resistance is interposed into the circuit under interruption at a sufficiently small rate to preclude occurrence of dangerous surge voltages incident to interruption of major fault currents.

When quartz sand having a relatively narrow range of particle sizes is being mixed intimately with another non-silicious arc-quenching filler having a much smaller thermal conductivity than quartz sand and evolving gases under the heat of electric arc, e.g. gypsum, the other filler having also a relatively narrow range of particle sizes, but the size of the particles of the other filler being much smaller than that of the particles of quartz sand, the particles of quartz sand are being coated by the other filler and form lumps the size of which is a multiple of their original size. This is readily apparent from FIGS. 4 and 5. If a relatively small amount of relatively fine gypsum powder is admixed to a relatively large amount of relatively coarse quartz sand, e.g. but 10% in volume of that of the quartz sand, then only a relatively small portion of the quartz grains will be gypsum coated, the balance of the particles of quartz sand remaining uncoated. There is a critical ratio of gypsum powder to quartz sand when about all the particles of the quartz sand are coated with gypsum powder, forming lumps, there being no significant excess of free gypsum powder, i.e. gypsum powder not forming part of a lump whose nucleus is a particle of quartz sand.

I have found that it is most desirable from the viewpoint of minimizing heat exchange between a current carrying fuse link and its surroundings and at the same time maximizing the cooling and deionizing action of the arc-quenching filler on blowing of the fuse to use a mixed filler having a considerably smaller content of gypsum than the above referred to critical ratio. The preferred grain size of quartz sand is 50 to 60 U.S. Sieve Number, and the preferred grain size of gypsum powder is in the order of 18 U.S. Sieve Number. The preferred mixture of such quartz sand and such a gypsum powder is about 30 volume percent of the gypsum powder admixed to about 70 volume percent of such a quartz sand. If it is desirable to obtain a fuse structure having sufficient time-lag to be applicable in motor circuits, then the additional filler phase, or the gypsum content of the mixture, must be sufficiently high to extend the fusing time of the link-severing overlay at currents in the order of five times the rated current of the fuse to several seconds, preferably as much as ten seconds. This can readily be achieved with a link geometry of the kind shown in FIGS. 1-3

and an arc-quenching filler being a mixture of about 70% quartz sand and about 30% gypsum powder. An increase of the content of gypsum powder beyond and above 30% of the volume of the content of quartz sand has virtually no effect upon minimum fusing current and rated current, respectively, but results in a significant reduction of arc voltage.

Referring now again to FIGS. 1-3 of the drawing, it will be apparent that the function of the low thermal conductivity phase of the filler, e.g. the gypsum phase thereof, is to minimize heat exchange between the surface of casing 1 and the center zone of the fuse link L_5 , L_5' , L_6 where the transverse center line of perforations 9 and the link-severing overlay 8 are located. This tends to derate the fuse link L_5 , L_5' , L_6 , calling for the addition of base metal, e.g. an increase in thickness, to restore the rating the fuse link had when rated in quartz sand. As a result, the blowing time at a given multiple of the rated current of the fuse structure is increased. The mere de-rating of reduction of the minimum fusing current by surrounding the center region of L_5 , L_5' , L_6 , including its link severing overlay 8, with a pulverulent arc-quenching filler having a relatively small thermal conductivity results in a reduction of the minimum fusing current, and hence of the current rating and, therefore, the fuse will blow within a given time at a higher multiple of the minimum fusing current, or the rated current, it had when filled with quartz sand rather than with a specific mixture of quartz sand and a finer arc-quenching filler having a much smaller thermal conductivity than quartz sand. This is but another expression of the fact that the time-lag of a fuse having a filler of quartz sand is increased by admixing to the quartz sand another arc-quenching filler having a smaller particle size and a smaller thermal conductivity than quartz sand.

If a fuse structure of the kind illustrated in FIGS. 1-3 and described in connection therewith blows on major fault currents, or short-circuit currents, the action of the quartz phase of the mixed filler becomes significant and results in the generation of a relatively high arc-voltage at each point of break, i.e. at the region of each of the transverse lines of perforations 9.

It will be apparent from the foregoing that an intimate mixture of relatively coarse quartz sand and relatively fine gypsum powder forms a more effective thermal barrier between the peak temperature region of fuse link L_5 , L_5' , L_6 when the latter is carrying current and which is situated in the median plane thereof and the radially juxtaposed region of casing 1 than a filler of quartz sand only. On the other hand, a mixture of coarse quartz sand and fine gypsum powder is capable of generating higher arc voltages than an arc-quenching filler of gypsum.

It will be apparent to those skilled in the art that various changes and modifications may be made in the fuse structure illustrated and described without departing from the spirit of the invention, as set forth in the appended claims.

I claim as my invention:

1. An electric time-lag fuse comprising in combination:
  - (a) a pair of spaced terminal elements;
  - (b) a tubular casing of insulating material closed on both ends thereof by said pair of terminal elements;
  - (c) a ribbon fuse link of a metal having a relatively high fusing point conductively interconnecting said pair of terminal elements, said fuse link defining a plurality of serially related zones of reduced cross-section;
  - (d) an overlay on said fuse link of a metal having a relatively low fusing point arranged in close proximity to one of said plurality of zones of reduced cross-section to cause severance of said fuse link by a metallurgical reaction on reaching by said overlay the fusing point of said low fusing point metal; and
  - (e) an intimate mixture of granular quartz and of an additional pulverulent arc-quenching filler embed-

ding said plurality of zones of reduced cross-section of said link and embedding said overlay, said additional filler having a substantially smaller thermal conductivity than said granular quartz as such, said additional filler further having a substantially smaller average particle size than said granular quartz, and said mixture having a sufficiently high content of said additional filler to coat the preponderant portion of the particles of said granular quartz and to extend the fusing time of said overlay at currents in the order of five times the rated current of the fuse to the order of several seconds.

2. An electric time-lag fuse comprising in combination:

- (a) a pair of spaced terminal elements;
- (b) a tubular casing of insulating material closed on both ends thereof by said pair of terminal elements;
- (c) a ribbon fuse link of a metal having a relatively high fusing point conductively interconnecting said pair of terminal elements, said fuse link defining a plurality of serially related zones of reduced cross-section;
- (d) an overlay on said fuse link of a metal having a relatively low fusing point arranged in close proximity to one of said plurality of zones of reduced cross-section to cause severance of said fuse link by a metallurgical reaction on reaching by said overlay the fusing point of said low fusing point metal; and
- (e) an intimate mixture of granular quartz and of an additional pulverulent arc-quenching filler embedding said plurality of zones of reduced cross-section of said fuse link and said overlay, said additional filler having a substantially smaller thermal conductivity than said granular quartz, said additional filler further having a substantially smaller average particle size than said granular quartz, and the additional filler phase of said mixture occupying a volume within said casing substantially less than the volume occupied by the granular quartz phase thereof in excess of 20% of the volume occupied by said granular quartz phase thereof.

3. An electric time-lag fuse comprising in combination:

- (a) a pair of spaced terminal elements;
- (b) a tubular casing of insulating material closed on both ends thereof by said pair of terminal elements;
- (c) a ribbon fuse link of a metal having a relatively high fusing point conductively interconnecting said pair of terminal elements, said fuse link defining a plurality of serially related zones of reduced cross-section;
- (d) an overlay on said fuse link of a metal having a relatively low fusing point arranged in close proximity to one of said plurality of zones of reduced cross-section to cause severance of said fuse link by a metallurgical reaction on reaching by said overlay the fusing point of said low fusing point metal; and
- (e) an intimate mixture of granular quartz and a pulverulent gypsum filler embedding said plurality of zones of reduced cross-section of said fuse link and said overlay, said gypsum filler having a substantially smaller thermal conductivity than said granular quartz, said gypsum filler further having a substantially smaller average particle size than said granular quartz, and gypsum filler of said mixture being in the order of 30 percent of the volume of said granular quartz.

4. An electric time-lag fuse comprising in combination:

- (a) a pair of spaced terminal elements;
- (b) a tubular casing of insulating material closed on both ends thereof by said pair of terminal elements;
- (c) a ribbon fuse link of a metal having a relatively high fusing point conductively interconnecting said pair of terminal elements, said fuse link defining a plurality of serially related zones of reduced cross-section;
- (d) an overlay on said fuse link of a metal having a

relatively low fusing point arranged in close proximity to one of said plurality of zones of reduced cross-section to cause severance of said fuse link by a metallurgical reaction on reaching by said overlay the fusing point of said low fusing point metal; and

- (e) an intimate mixture of quartz sand having a grain size in the order of 50 to 60 U.S. Sieve Number and of gypsum powder having a grain size in the order of 18 U.S. Sieve Number embedding said plurality of zones of reduced cross-section of said link and embedding said overlay, and the gypsum powder phase of said mixture occupying a volume within said casing about one third as large as the volume occupied by said quartz sand phase thereof.

5. An electric time-lag fuse comprising in combination:

- (a) a pair of spaced terminal elements;
- (b) a tubular casing of insulating material closed on both ends thereof by said pair of terminal elements;
- (c) a ribbon fuse link of a metal having a relatively high fusing point conductively interconnecting said pair of terminal elements, said fuse link defining a plurality of serially related zones of reduced cross-section;

(d) an overlay on said fuse link of a metal having a relatively low fusing point arranged in close proximity to one of said plurality of zones of reduced cross-section to cause severance of said fuse link by a metallurgical reaction on reaching by said overlay the fusing point of said low fusing point metal; and

- (e) an intimate mixture of a plurality of pulverulent arc-quenching fillers embedding said plurality of zones of reduced cross-section of said fuse link and embedding said overlay, said mixture comprising a quartz sand and a non-silicious phase of a substance decomposing under the heat of electric arcs having a substantially smaller average particle size and a substantially smaller thermal conductivity than said quartz sand, and the non-silicious phase of said mixture being sufficiently high to coat the preponderant portion of the particles of said quartz sand and to extend the fusing time of said overlay at currents in the order of five times the rated current of the fuse to the order of several seconds.

6. An electric time-lag fuse comprising in combination:

- (a) a pair of spaced terminal elements;
- (b) a tubular casing of insulating material closed on both ends thereof by said pair of terminal elements;
- (c) a pair of ribbon fuse link structures inside of said casing conductively interconnecting said pair of terminal elements, said pair of fuse link structures comprising a base metal having a relatively high fusing point and each of said pair of fuse link structures defining a plurality of serially related zones of reduced cross-section, each of said pair of fuse link structures including a first portion arranged relatively close to the longitudinal axis of said casing and each of said pair of fuse link structures further including a second portion arranged generally more remotely from said longitudinal axis and overlapping and shunting said first portion;

(d) an overlay on each of said pair of fuse link structures of a metal having a relatively low fusing point arranged in close proximity to one of said plurality of zones of reduced cross-section to cause severance of each of said pair of fuse link structures by a metallurgical reaction on reaching by said overlay the fusing point of said low fusing point metal; and

- (e) an intimate mixture of granular quartz and of an additional pulverulent arc-quenching filler embedding all of said plurality of zones of reduced cross-section and said overlay of each of said pair of fuse link structures, said additional filler having a substantially smaller average particle size than said granular quartz and a substantially smaller thermal conductivity than said granular quartz, the volume of the granular

quartz content of said mixture being at least twice the volume of said additional filler and the volume of said additional filler being sufficiently large to coat substantially all particles of said granular quartz with said additional filler.

7. An electric time-lag fuse as specified in claim 6 wherein said additional arc-quenching filler is gypsum powder.

8. An electric fuse comprising in combination:

(a) a pair of spaced terminal elements;

(b) a tubular casing of insulating material closed on both ends thereof by said pair of terminal elements;

(c) a pair of ribbon fuse links inside said casing conductively interconnecting said pair of terminal elements, said pair of fuse links comprising a base metal having a relatively high fusing point and each of said pair of fuse links defining a plurality of serially related zones of reduced cross-section, each of said pair of fuse links being substantially channel-shaped and each of said pair of fuse links including a relatively wide web portion and a pair of relatively narrow integral flange portions each enclosing an angle of less than 90 degrees with said web portion thereof;

(d) an overlay on each of said pair of fuse links of a metal having a relatively low fusing point extending transversely across said web portion and across said pair of flange portions of each of said pair of fuse links, to cause severance of each of said pair of fuse links by a metallurgical reaction on reaching by said overlay the fusing point of said low fusing point metal; and

(e) an intimate mixture of granular quartz and of an additional pulverulent arc-quenching filler embedding all of said plurality of zones of reduced cross-section and said overlay of each of said pair of fuse links, said additional filler having a substantially smaller average particle size than said granular quartz and a substantially smaller thermal conductivity than said granular quartz, the volume of the granular quartz content of said mixture being at least twice the volume of said additional filler and the volume of said additional filler being sufficiently large to coat substantially all particles of said granular quartz with said additional filler.

9. An electric time-lag fuse having a predetermined rated current and comprising in combination:

(a) a pair of spaced terminal elements;

(b) a tubular casing of insulating material closed on both ends thereof by said pair of terminal elements;

(c) a pair of ribbon fuse links of a metal having a relatively high fusing point conductively interconnecting said pair of terminal elements, said pair of fuse links comprising a base metal having a relatively high fusing point and each of said pair of fuse links having a plurality of transverse lines of perforations, each of said plurality of fuse links being substantially channel-shaped and each of said pair of fuse links including a relatively wide web portion and a pair of relatively narrow flange portions each enclosing an acute angle with said web portion thereof;

(d) a pair of overlays each on one of said pair of fuse links each of a metal having a relatively low fusing point and each arranged in close proximity to one of said plurality of transverse perforations to cause severance of said pair of fuse links by a metallurgical reaction on reaching by said pair of overlays the fusing point of said low fusing point metal; and

(e) an intimate mixture of granular quartz and of an additional pulverulent arc-quenching filler embedding said plurality of transverse lines of perforation of said pair of fuse links and said pair of overlays, said additional filler having a substantially smaller thermal conductivity than said granular quartz as such and being present in a sufficiently high proportion to extend the fusing time of said overlay at currents of

about five times the rated current of said fuse to the order of ten seconds.

10. An electric time-lag fuse having a predetermined rated current and comprising in combination:

(a) a pair of spaced terminal elements;

(b) a tubular casing of insulating material closed on both ends thereof by said pair of terminal elements;

(c) ribbon fuse link means of a metal having a relatively high fusing point conductively interconnecting said pair of terminal elements, said fuse link means having a plurality of transverse lines of perforations defining a plurality of serially related points of reduced cross-section, and said fuse link means further having a pair of lateral current-carrying fin portions bent out of the general plane defined by said fuse link means and enclosing a predetermined acute angle with said general plane;

(d) overlay means on said fuse link means having a relatively low fusing point arranged in close proximity to one of said transverse lines of perforations to cause severance of said fuse link means by a metallurgical reaction on reaching by said overlay the fusing point of said low fusing point metal; and

(e) an intimate mixture of granular quartz and of an additional pulverulent arc-quenching filler inside said casing embedding all of said plurality of lines of transverse perforations of said fuse link means and said overlay means thereof, said additional filler having a substantially smaller thermal conductivity than said granular quartz as such, said additional filler having a substantially smaller average particle size than said granular quartz, and said additional filler being present in sufficiently high proportion to coat substantially all the grains of said quartz thereby substantially increasing the size thereof and to extend the fusing time of said overlay on currents of about five times said rated current of said fuse to the order of ten seconds.

11. An electric time-lag fuse having a predetermined rated current and comprising in combination:

(a) a pair of spaced terminal elements;

(b) a tubular casing of insulating material closed on both ends thereof by said pair of terminal elements;

(c) a pair of ribbon fuse link means of a metal having a relatively high fusing point arranged inside said casing and conductively interconnecting said pair of terminal elements, each of said pair of fuse link means having a plurality of transverse lines of perforations defining a plurality of serially related points of reduced cross-section, and each of said pair of fuse link means being bent transversely to define a cavity extending in a direction longitudinally of said casing limiting heat exchange between said fuse link means and a medium surrounding said casing;

(d) a pair of overlays each on one of said pair of fuse link means, said pair of overlays being made of a metal having a relatively low fusing point and being arranged in close proximity to one of said plurality of transverse lines of perforations of one of said pair of fuse link means to cause severance thereof by a metallurgical reaction on reaching by said pair of overlays the fusing point of said low fusing point metal; and

(e) an intimate mixture of granular quartz sand and of an additional pulverulent arc-quenching filler within said casing inside and outside of said cavity defined by said fuse link means, said additional filler having a substantially smaller thermal conductivity than said granular quartz as such, said additional filler having a substantially smaller average particle size than said granular quartz and said additional filler being present in sufficiently high proportion to coat the grains of said quartz thereby substantially increasing the size thereof and to extend the fusing time of said overlay on currents of about five times

11

said rated current of said fuse to the order of ten seconds.

12. An electric time-lag fuse comprising in combination:

- (a) a pair of spaced terminal elements;
- (b) a tubular casing of insulating material closed on both ends thereof by said pair of terminal elements;
- (c) a unitary fuse link of a metal having a relatively high fusing point inside said casing extending from one of said pair of terminal elements across the median plane of said casing to the other of said pair of terminal elements, said link defining a plurality of serially related zones of reduced cross-section and establishing a peak temperature region situated substantially at the median plane of said link;
- (d) an overlay on said link of a metal having a relatively low fusing point arranged in close proximity to said median plane of said link to cause severance of said link by a metallurgical reaction on reaching by said overlay the fusing point of said low fusing point metal; and

(e) an intimate mixture of granular quartz and of an additional pulverulent arc-quenching filler embedding said plurality of zones of reduced cross-section and embedding said overlay and separating said overlay from the radially juxtaposed region of said casing, and said additional filler having a substantially smaller average particle size and a substantially smaller thermal conductivity than said granular quartz.
